UNITED STATES PATENT OFFICE.

WILLIAM R. HOTCHKISS, OF ST. PAUL, MINNESOTA.

PRINTING PRESS.

Application filed June 15, 1923. Serial No. 645,580.

To all whom it may concern:

Be it known that I, WILLIAM R. HOTCHKISS, a citizen of the United States, residing at St. Paul, in the county of Ramsey and State of Minnesota, have invented new and useful Improvements in Printing Presses, of which the following is a specification.

The object of this invention is to provide an unusually high speed and efficient press particularly adapted for check printing and other work usually performed on platen presses.

Referring to the accompanying drawings, which illustrate the best form of my device at present known to me, Figure 1 is an end elevation of my improved press; Fig. 2 is a side elevation of the same showing the bed in the position for setting up a plate or type form thereon, Fig. 3 is a section taken on the line 3—3 of Fig. 2 showing the several cylinder supporting parts in lowered or printing position; Fig. 4 is an end view of the cylinder and inking mechanism; Fig. 5 is a central, transverse section through the cylinder; Fig. 6 is a horizontal section taken on the line 6—6 of Fig. 3 and showing a fragmentary portion of the cylinder; Fig. 7 is a section taken on the line 7—7 of Fig. 2 showing the bed in operating position and elevated; Fig. 8 is a side elevation of the cylinder with the ink plate removed; Fig. 9 is a section through the cylinder taken on the line 9—9 of Fig. 7; and Fig. 10 is a detail elevation of the inner face of the ink plate.

In the accompanying drawings I have used the numeral 11 to indicate a pair of standards connected by transverse members 12 to form a supporting frame for the press. A flange 13 extends around the outer surface of each of the standards 11 and similar flanges 14 (Figs. 1 and 6) form vertical guides for slides 15 in said standards. The slides 15 are free to move vertically within the limits of rectangular openings 16 in the standards 11. Projecting laterally from each of the slides 16 is a pair of flanges 17 which bear against the inner surfaces of the standards 11. Supported near its ends upon the slides 15 is a large shaft 18 carrying a cylinder 19. The shaft 18 is rigidly

secured to the slides 15 by taper pins 20, the removal of said pins from the shaft being facilitated by nuts 21 threaded on the upper ends of said pins and arranged to be turned downward to withdraw said pins from the shaft.

The cylinder 19, as best shown in Figure 5, has an axial bore 22 through which the shaft 18 passes. Extending through the cylinder 19 from one end to the other are cored out portions 23 and a compartment 24 closed on its periphery by an ink plate 25. The normally lower portion of the cylinder 19 is flattened to receive a bed plate 26 upon which the usual chase 27 is carried. The type or electrotype plate 28 is mounted in the usual manner in the chase 27. As shown, the chase 27 is rigidly secured to the bed plate 26 which is held in place at one edge by an under cut portion 29 of the cylinder and at the opposite edge by a suitable screw 30.

A series of spring actuated rods 31 extend radially through the cylinder 19 and normally project into the bore 22, where they engage suitable recesses 32 in the shaft 18. The rods 31 are connected in pairs at their outer ends by suitable grips 33 while coiled springs 34 normally press said rods into engagement with the shaft 18 in the recesses 32. By means of the grips 33, the rods 31 may be withdrawn from the recesses 32 and the cylinder 19 rotated upon the shaft 18 to either the operative position shown in Figs. 4, 5 and 7, or to the inoperative position shown in Figs. 1 and 2.

Vertical reciprocating movement is imparted to the shaft 18 carrying the cylinder 19 by a pair of large pitmen 35 pivotally joined at their upper ends to the outer ends of the shaft 18 and adapted to be actuated by cranks 36 on the outer extremities of a power shaft 37. This latter shaft may be driven by any suitable means, such as by an electric motor connected to a gear 38 on the shaft 37. When the shaft 37 is rotated, the motion thus imparted to the cylinder 19 causes the plate 28 on the bed 26 to be reciprocated so as to make impressions upon paper placed on a platen 39 supported by the standards 11.

Ink is applied to the type 28 by a pair of

composition rollers 40 which oscillate over said type and the ink plate 25 at each stroke of the cylinder. The composition rollers 40 are carried by pairs of arms 41 which are 5 slidable in sockets 42. The rollers are maintained in contact with the periphery of the cylinder 19 by springs 43 acting upon the arms 41 within the sockets 42. At the ends of the cylinder 19 the arms 41 are connected in pairs by bars 44 which also act as counter weights. The sockets 42 are also connected in pairs by gears 45 adapted to 10 rotate on the shaft 18. Meshing with each of the gears 45 is a vertical rack 46 sliding 15 in a guide 47 on the inner face of each of the standards 11. The racks 46 are severally joined by links 48 and 49 and levers 50 with the slides 15, the levers 50 being tiltably mounted upon pins 51 on the inner 20 faces of the standards 11. By this system of linkage, the racks 46 are elevated to rotate the gears 45 in one direction when the slides 15 are moved downward while the racks 46 are moved downward to rotate the 25 gears 45 in the reverse direction when the slides 15 are elevated. As the slides 15 reciprocate, the arms 41 carrying the composition rollers 40 are thus oscillated over the ink plate 25 and type. Opposite, extreme positions of the parts of the printing mechanism are severally shown in Figs. 4 and 7.

A spring actuated counterbalance for 30 reciprocating movement of the cylinder 19 is provided. This counterbalance consists of a pair of stout springs 52 supported upon brackets 53 on the standards 11 and levers 54 pivotally supported at one end upon a transverse rod 55 and joined to the slides 40 15 by links 56, the free ends of the levers 54 being supported upon the springs 52. The tension in the springs 52 is made adjustable by means of nuts 57 and compression rods 57^a so that the momentum of the 45 reciprocating parts is opposed by the springs 52.

To properly distribute ink on the composition rollers 40, the ink plate 25 is given longitudinal reciprocating movement by the 50 following described mechanism. The plate 25 (Figs. 5 and 8 to 10, inclusive) is movable in longitudinal guide ways 58 in the cylinder 19, said plate being somewhat shorter than said guide ways. The plate 25 is retained within the guide ways by a longitudinal rod 59 which is fastened at its 55 ends in ears 60 on the cylinder. The rod 59 passes freely through ears 61 on the plate 25 and through a suitable aperture in a yoke 62 which is bolted to the inner surface of 60 said plate. Thus, the plate 25 is free to slide on the rod 61 in the guide ways 58. A small roller 63, mounted eccentrically 65 upon a wheel 64, extends into the yoke 62. The wheel 64 is secured to the face of a

ratchet wheel 65, said ratchet being mounted concentrically with the wheel 64 upon a pivot pin 66 (Fig. 9) of a lever 67. One end of the latter lever is adapted to be actuated by a roller 68 mounted on the inner 70 face of one of the sockets 42. The opposite end of the lever 67 carries a pawl 69 which engages the ratchet 65. A spring 70 secured at one end to the normally upper edge of the lever 67 and at its other end to the cylinder 19 maintains the lever 67 in its full line position shown in Figure 8, except when actuated by the roller 68. As the gear 45 oscillates the composition rollers 40, the small roller 68 strikes a bearing plate 71 on the lever 67 and moves said lever to its dotted line position shown in Figure 8, at the end of the stroke the composition rollers being in the position shown in Figure 7. As the roller 68 is carried back toward the position shown in Figure 4, the spring 70 acts to return the lever 67 to the full line position shown in Figure 8. Upon each downward stroke of the lever 67, the pawl 69 turns the ratchet 65 together with the wheel 90 80 85 95 100 105 110 115 120 125 130 135 140 145 150 155 160 165 170 175 180 185 190 195 200 205 be printed may either be fed to the platen 39 by hand or by any suitable power driven feeding mechanism. Ink may be applied to the plate 25 either by hand or by any well known or suitable automatic feed mechanism.

Important features of the present device are the arrangement by which an unusually short printing stroke is obtained and the 10 unusually light weight of the reciprocating parts as compared with presses in common use. The present machine is thus adapted to work at a very high rate of speed. As is well known, with the old type of platen 15 press a speed of about 2000 impressions per hour is about the maximum that has been attainable without sacrificing accuracy. On the other hand, with the present machine a speed of from 5000 to 6000 impressions per 20 hour is obtainable, while retaining a high degree of accuracy. By providing long slides 15 for guiding the vertical movement of the cylinder 19, all possibility of lateral play and inaccuracy of making impressions 25 is eliminated. The high speed and accuracy of the present device greatly reduces the cost of printing and renders the machine peculiarly adapted for use in printing checks or other forms or coupons where a 30 large number of copies are required.

Having described my invention what I claim as new and desire to protect by Letters Patent is:

1. In a printing press, a platen and bed 35 arranged in parallel relation, said bed being adapted to carry type for printing on said platen, a revoluble cylinder supporting said bed on its periphery, inking mechanism on said cylinder, manually operable means for 40 rotating said cylinder to render said bed accessible and means for imparting reciprocating movement to said cylinder whereby printing is effected.

2. In a printing press, a frame, a platen 45 and bed normally arranged in parallel relation with each other, said bed being adapted to carry type for printing on said platen, a cylinder revolvably supported in said frame and carrying said bed on its periphery, an 50 ink plate in the periphery of said cylinder, means for imparting reciprocating movement to said cylinder whereby printing is effected, means arranged to distribute ink from said plate to type on said bed, and 55 means for releasing said cylinder to permit revolving the same whereby said bed may be rotated out of parallel relation with said platen.

3. In a printing press, a frame, a normally 60 stationary platen disposed horizontally in said frame, a bed adapted to be superimposed on said platen and arranged to carry type for printing on said platen, a vertically reciprocable and tiltable support for said bed, means for imparting reciprocating

movement to said support for printing, means for maintaining said bed in parallel relation with said platen during said reciprocating movement, and means for tilting said support and bed out of parallel relation with said platen to allow access to said bed.

4. In a printing press, a platen and bed normally arranged face to face, said bed being adapted to carry type for printing on said platen, a substantially cylindrical support for said bed, a shaft extending axially through said cylindrical support in parallel relation with said platen and bed, means normally operative to rigidly secure said support on said shaft, means for imparting reciprocating movement to said shaft in a direction perpendicular to said platen, and manually operable means for rotating said support on said shaft to render said bed accessible.

5. In a printing press, a bed support formed with a plain surface adapted to receive a printer's form for type, a frame, a platen mounted in said frame face to face with said surface, reciprocable slides disposed in said frame adjacent to opposite ends of said support, means pivotally joining said support to said slides, means normally operative to rigidly secure said support on said slides, inking mechanism carried by said support and means for imparting reciprocating movement to said slides and support for printing on said platen.

6. In a printing press, a hollow bed support formed with a central bearing and a plain surface adapted to receive a printer's form for type, a frame, reciprocable slides disposed in said frame adjacent to opposite ends of said support, a shaft connecting said slides and extending through said bearing in said support, means normally operative to rigidly secure said support on said shaft, gears revoluble on said shaft near the ends of said support, an ink carrier mounted on said support, a roller adapted to distribute ink from said carrier to type on said support, a pair of arms connecting the ends of said rollers with said gears, means for imparting reciprocating movement to said slides and means operatively connecting said slides with said gears whereby said gears are oscillated upon said shaft when said slides are actuated.

7. In a printing press, a hollow bed support formed with a central bearing and a plain surface adapted to receive a printer's form for type, a frame, reciprocable slides disposed in said frame adjacent to opposite ends of said support, a shaft connecting said slides and extending through said bearing in said support, means normally operative to rigidly secure said support on said shaft, an arcuate ink plate slidable longitudinally on said support, gears revoluble on said shaft adjacent to the ends of said support, a roller

adapted to distribute ink from said plate to type on said support, a pair of arms connecting the ends of said roller with said gears, means actuated by one of said arms for transmitting reciprocating movement to said ink plate, means for imparting reciprocating movement to said slides and means

operatively connecting said slides with said gears whereby said gears are oscillated upon said shaft when said slides are actuated.

In testimony whereof, I have hereunto signed my name to this specification.

WILLIAM R. HOTCHKISS.
